UNITED STATES PATENT OFFICE.

ASMUS JABS, OF ZURICH, SWITZERLAND.

ELECTRIC MASTER-CLOCK.

1,118,422.

Specification of Letters Patent. Patented Nov. 24, 1914.

Application filed May 5, 1914. Serial No. 836,459.

To all whom it may concern:

Be it known that I, ASMUS JABS, a subject of the Emperor of Germany, and a resident of Zurich, Switzerland, have invented 5 new and useful Improvements in Electric Master-Clocks; and I do hereby declare the following to be a full, clear, and exact description of the invention, such as will enable others skilled in the art to which it applies 10 to make and use the same, reference being had to the accompanying drawings, and to letters or figures of reference marked thereon, which form a part of this specification.

15 This invention relates to improvements in the arrangement of the contacts of electric master-clocks.

For the purpose of driving a large number of receiving or secondary clocks from 20 an electric master-clock it has already been proposed to impart to said secondary clocks at fixed or predetermined time intervals an electric current impulse, so that the points of said clocks moved by jerks are rotated in 25 a uniform manner.

In the arrangement of contacts of electric master-clocks according to this invention there is provided a current reverser-contact, which is rotated mechanically and continually 30 by means of a clock-work actuated, for instance, in a known manner by a weight. Within reach of the path of rotation of the current reverser-contact there are provided contact-levers, some of which are electrically 35 connected to a battery circuit, while the others are electrically connected to the circuit of the secondary clocks. In the hitherto proposed master-clocks there have been provided as contact-pieces so called contact- 40 keys which were rotated only temporarily to close the contact and which afterward remained stationary for a certain interval of time. The provision of a mechanically and continually rotated current reverser-contact 45 has the advantage to secure a uniform movement free of jerks and it permits of making very short contacts, so that no sparks are formed and the contacts can be kept longer closed. This current reverser-contact may 50 be combined with means, which reduce the duration of the contact to a greater amount than the mechanical drive of the current reverser-contact permits to reduce, for instance, there may be provided a second re- 55 volving contact positively connected to said current reverser-contact. This second con-

tact moves then quicker than the current reverser-contact and it may be arranged in one of the two hereinbefore mentioned circuits, for instance in the battery circuit. 60

Several modes of carrying this invention into effect are shown by way of example in the accompanying drawings, in which:

Figure 1 shows a front elevation of a first construction embodying my invention, 65 Fig. 2 shows a side-view of this construction, Fig. 3 shows a plan-view of the current reverser-contact, Fig. 4 shows a section on the line A—B of Fig. 3, Fig. 5 shows a longitudinal section of said reverser-contact, Fig. 6 shows a front elevation of a second construction embodying my invention, 70 Fig. 7 shows a side view of this second construction, Fig. 8 shows the connection scheme used in these two constructions embodying my invention, Fig. 9 shows a front elevation of a third construction according to this invention and Fig. 10 shows a corresponding elevation illustrating the different 75 parts of this third construction in another position, Fig. 11 shows a side elevation of this third construction and Fig. 12 shows a section on the line C—D of Fig. 11. Figs. 13 and 14 show the connection-scheme of 80 this third mode of carrying out the invention for different positions of the current reverser-contact.

In carrying the invention into effect according to the construction as shown in Figs. 1 to 5 a toothed wheel 1 of the clock-work which may be actuated for instance by a weight, drives mechanically a toothed wheel 2. The bush 3 of this toothed wheel 2 is loosely mounted on a shaft 4. A pin 5 fixed to a lever 6 projects into the space provided between the spokes of the wheel 2. The lever 6 is rigidly connected to a contact-piece W, which acts as a current reverser. Said lever 6 and the current reverser-contact-piece W are rigidly connected to the 95 shaft 4. The current reverser-contact W, which is more clearly illustrated in Figs. 3 to 5, has an insulating core 7 on both sides of which there are fixed electric current conducting sheet-irons 8 and 9. These sheets 8 and 9 are insulated from each other. The sheet 9 has at one end a tongue 10 and at the other end two tongues 11 and 12. The sheet 8 has at one end a tongue 13 and at the other end two tongues 14 and 15. The tongue 10 of the sheet 9 and the tongue 13 of the sheet 8 are arranged in one straight 100 105 110

line side by side just as also the tongues 12 and 11 of the sheet 9 and the tongues 14 and 15 of the sheet 8 on the other end are in a straight line side by side. Two arms 16 (Fig. 2) are mounted on an enlarged part 5 of the shaft 4. The ends of these arms are connected by means of the parts 17. The arms 16 and the parts 17 form a frame-like armature, the longitudinal axis of which is 10 arranged diagonally to the longitudinal axis of the current reverser-contact W (see Fig. 1). While the parts 17 are rotated they pass near the pole-shoes 18 of an electro-magnet 19, which, as shown in Fig. 8, is 15 arranged in a separate circuit α . A circuit α is connected to said separate circuit α , the secondary clocks N being arranged in the circuit α . Below the revolving contact W there are disposed four contact-levers 21, 20 22, 23, 24, which are insulated one from another. The contact-levers 21, 24 form the ends of the battery circuit, while the contact-levers 22, and 23 form the ends of the separate circuit α . These contact-levers are 25 loosely and pivotally mounted on the shaft 20 and they are insulated from this shaft. The rear, heavier ends of said contact-levers rest on a support 25. According as the one or the other side of the current reverser-contact 30 W engages said contact-levers, the direction of the current impulse transmitted to the secondary clocks will be altered, as can easily be seen from Fig. 8, so that a magnetization of the different parts of the 35 clock is prevented. The armature 16, 17, the current reverser-contact W and the lever 6 together with the pin 5 are fixed to the shaft 4, while the toothed wheel 2, between whose spokes projects the pin 5, is loosely mounted 40 on the shaft 4. Owing to this arrangement, a rotation of the toothed wheel 2 in the direction of the arrow shown in Fig. 1 causes a continual rotation of the reverser-contact W, because a spoke of the wheel 2 bears 45 against the pin 5. As soon, however, as the circuit γ (Fig. 8) is closed in which case the different members are in the position illustrated in Fig. 1, also the circuit α will be closed and the electro-magnet 19 will 50 then be excited. This causes in the first place a transmission of a current impulse to the secondary clocks N and secondly the contact between the revolving pieces W and the levers 21 and 24 will be opened, since 55 the armature part 17 lying nearer the pole-shoe 18 will be quickly attracted by the electro-magnet 19 as soon as the circuit α is closed. In this manner all the contacts are opened more quickly than would be the 60 case if the reverser-contact W were mechanically rotated by the toothed wheel 2. During this quick rotary motion of the shaft 4 the toothed wheel 2 will not be rotated, the pin 5 having a certain amount of play between the spokes of the toothed wheel 2. 65

The toothed wheel 2 rotates farther without acting upon the shaft 4 till its spoke bears again against the pin 5. Hereupon the rotating contact will be continually rotated in a mechanical manner till the next contact-closing takes place, a current impulse directed in the reverse direction being then transmitted to the secondary clocks N. 70

In carrying the invention into effect according to the construction as shown in Figs. 6 and 7 the contact-lever 24 has on its front end a nose 26, over which may project, as will be hereinafter described, a lever 27 acted upon by a spring 28. On the shaft 4 there is further mounted a lever 29 having a pin 30. The heavier rear ends of the levers 21 to 24 rest on an arm 31 of a lever, which carries on its other end the armature 32. Shortly after the revolving contact W has reached the closing position shown in Fig. 6, 80 the electro-magnet 19 will be excited, so that it attracts the armature 32. This has the effect to lower all the contacts 21 to 24. Hereby the nose 26 comes to rest below a nose of the lever 27, so that the lever 24 will 85 not be moved upward when the current exciting the electro-magnet 19 is opened, but will remain in the depressed position. As soon, however, as said pin 30 strikes against the lever 27, while the rotating contact W 90 is in the position to make contact with the levers 21 to 23, said lever is moved outward against the tension of the spring 28 and the lever 24 will then be moved toward the current reverser-contact W, this being the preliminary step toward the excitation of the electro-magnet 19 or toward the closing of the circuit γ . 95

According to the construction illustrated in Figs. 9 to 14 the rotating contact W is 105 rigidly connected to a toothed wheel 33, receiving its drive from a clock-work. A toothed wheel 34 gears into the toothed wheel 33. The diameter of the wheel 33 is a multiple of the diameter of the wheel 34, 110 for instance in the present case said diameter is four times greater than that of the wheel 34. A contact-piece 35 is connected to the toothed wheel 34, said piece 35 being rotated four times quicker than the current reverser-contact W. The contact-piece 35 is, however, not arranged in a circuit and it serves only to connect electrically for a time two contact-pieces 37 and 38 by means of a pin 36 (see Figs. 13 and 14). These two contacts 37, 38 form a break in the battery circuit γ . In this case no separate circuit α is provided for. It will be evident that a closing of the contacts takes place only during each second revolution of the second contact-piece 35. As shown in Fig. 9, the contact piece 35 could also make contact during its first revolution, but the current reverser-contact W is not in the proper position for making contact, so that the contact made be- 120 125 130

tween the parts 36, 37 and 38 is in this case of no value. As shown in Fig. 10, contact will be made only during the following revolution, both the contact-pieces being then in 5 the proper position required for making contact. As the speed of rotation of the contact-piece 35 is a multiple of that of the current reverser-contact W, the contact on the pieces W will accordingly be opened in a 10 much quicker manner than the mechanical drive of the current reverser-contact W would permit to open. From the Figs. 13 and 14 it will be seen that according to the 15 position of the reverser-contact W the current impulse transmitted to the secondary clocks will have a different direction.

What I claim is:

1. In an electric master-clock, a current reverser-contact, means for mechanically and 20 continually rotating said contact, contact-levers arranged within reach of the path of rotation of said reverser-contact, a part of said levers being arranged in a battery circuit and the other part in a circuit connected with secondary 25 clocks.
2. In an electric master-clock, a current reverser-contact, means for mechanically rotating said contact, contact-levers arranged within reach of the path of rotation of said 30 reverser-contact, a part of said levers being arranged in a battery circuit and the other part in a circuit connected with secondary clocks, and means for rendering the duration 35 of the contact shorter than the mechanical drive for said current reverser-contact permits to make.

3. In an electric master-clock, a current reverser-contact, means for mechanically and continually rotating said contact in a uniform manner, contact-levers arranged within 40 reach of the path of rotation of the current reverser-contact, a part of said levers being arranged in a battery circuit and the other part in a circuit connected with secondary clocks, a second rotating contact positively 45 connected to said reverser-contact, the speed of rotation of the second contact being a multiple of that of the reverser-contact and said second contact being arranged in one of the two mentioned circuits. 50

4. In an electric master-clock, a current reverser-contact, means for mechanically and continually rotating said contact in a uniform manner, contact-levers arranged within 55 reach of the path of rotation of the current reverser-contact, a part of said levers being arranged in a battery circuit and the other part in a circuit connected with secondary clocks, a second rotating contact positively 60 connected to said reverser-contact, the speed of rotation of the second contact being a multiple of that of the reverser-contact and said second contact being arranged in the battery circuit.

In testimony that I claim the foregoing as 65 my invention, I have signed my name in presence of two subscribing witnesses.

ASMUS JABS.
